D. F. DOWNES

HOOD LOCK

Filed April 12, 1920

Inspector.

Dennis F. Downes
By: B. Singer, Atty.

UNITED STATES PATENT OFFICE.

DENIS F. DOWNES, OF COBURG, NEAR MELBOURNE, VICTORIA, AUSTRALIA.

HOOD LOCK.

Application filed April 12, 1920. Serial No. 373,292.

To all whom it may concern:

Be it known that I, DENIS FRANCIS DOWNES, a subject of the King of Great Britain, residing at 31 Coburg Street, Coburg, near Melbourne, in the State of Victoria, Commonwealth of Australia, have invented new and useful Improvements in Hood Locks, of which the following is a specification.

10 This invention relates to an improved bonnet lock for securing motor-cars and like vehicles against unauthorized use and interference.

The facility with which motor-cars can be 15 started and rapidly driven away renders them extremely liable to be stolen, even from stations in city streets and in broad daylight. Furthermore, many improvements in the construction of motor-cars 20 make possible the rapid disassembling of component or attached parts, such for example as the magneto. The loss by theft of such vital parts of the mechanism as are costly, saleable and readily removable is of common 25 occurrence.

Locks have been applied as a preventative measure to the switches of motor-cars, but the protection afforded is not of great value as an intending thief with a knowledge of 30 motor-car work can simply lift the bonnet and re-wire the car so as to remove the locked switch from the circuit.

According to the present invention a 35 spring actuated bolt is mounted on the inner side of the bonnet lid of the vehicle while a hasp mounted on the bonnet board of said vehicle is adapted to be engaged automatically by the spring bolt when the bonnet is in the closed position, a pin and barrel lock 40 being provided for operating mechanism for the disengagement of the spring bolt from the hasp. In order to disengage the spring bolt from the hasp an arm is secured to the rotatable member of the lock and engages with the spring bolt. The spring bolt 45 is mounted in a frame secured to the inner side of the bonnet, this frame being provided with guide walls for the reception of the hasp to prevent endwise movement of the 50 bonnet lid. The spring bolt is prevented

from turning in the frame and is provided with a bevelled end adapted to cooperate with the rounded end of the hasp which is provided with a bevelled corner to facilitate its entry between the guide walls in the 55 frame.

The spring bolt pin and barrel lock and the bolt disengaging mechanism are enclosed in the frame by a cover clamped between the bonnet and the frame. 60

In order that the invention may be clearly understood reference is made to the accompanying explanatory drawings wherein:

Figures 1, 2 and 3 are perspective views 65 illustrating the application of the improved security device to the bonnet of a motor-car.

Figures 4, 5, 6, 7 and 8 illustrate in perspective component parts of the security device shown in Figures 1, 2 and 3.

Figures 9 and 10 are views in front elevation and in plan, respectively, of the locking device with the cover removed for the purpose of clearness in illustration. 70

In the drawings the numeral 14 designates the hingedly attached bonnet lid of a motor-car, and 15 and 16 indicate the bonnet board and dashboard, respectively, of the vehicle. 75

To the bonnet board 15 and inside the fall line 17 of said bonnet lid 14 there is securely 80 fastened a hasp 18. This hasp is preferably formed, as is shown in Figure 8, from a piece of strip metal, which is bent double at 19 and flanged outwardly at both ends 20. A bolt hole 21 and an entrance incline 22 85 are furnished in said hasp 18 and the bend 19 may be reinforced by rivets 23, if so required. The top 19¹ of said bent portion 19 is rounded and one corner 19² is bevelled.

A lock frame 24 is secured as by blind- 90 riveting 25 to the inner side of said bonnet lid 14 and in alignment with the hasp 18. This lock frame 24 has attachment flanges 26, a hasp-slot 27 and bolt guiding walls 28 and 29. In said walls 28 and 29 there are 95 formed bolt holes 30 which, when the bonnet lid is closed, are in alignment with said bolt hole 21 in the hasp.

Formed in the rear wall 31 of said lock frame 24 is a longitudinal slot 32. A bolt 33 100

is slidably mounted in said bolt-holes 30 and has a guide pin 34 which slides in said slot 32 and functions to prevent angular movement of said bolt 33.

5 A coil spring 35 is mounted on the bolt 33 and exerts pressure on said guide pin 34 tending to force said bolt in one direction as far as the dimensions of the slot 32 will permit. The end 37 of said bolt is chamfered on the underside as indicated by 10 in Figure 7.

An operating mechanism 39 is mounted in said lock frame 24, and has a member 40 which is adapted to be partially rotated by 15 a key 41 or the like. To this member 40 there is attached an arm 42 designed to contact with said guide pin 34 and thereby impart rectilinear motion to the bolt 33. In a preferred construction and as illustrated in the drawings, said operating mechanism 39 is a standard pin and barrel lock unit adapted to be operated by fluted and serrated keys.

A cover 43 is detachably fitted on the inside of the frame 24 in such manner that said frame must be removed from the bonnet lid 14 before said cover can be detached and the operating mechanism 39 and bolt 33 disclosed. Said cover 43 has a hole 44 corresponding with a key aperture 44¹ formed in the bonnet lid 14 and a pivotally attached lid 44² covers said aperture.

The action of the device is automatic and engagement of the bolt 33 and the hasp 18 follows upon the fall of the bonnet lid 14 onto the bonnet board 15.

When said bonnet lid 15 is lowered to the position shown in Figure 13, the hasp 18 enters the hasp-slot 27, being guided into 40 the same by the bevelled corner 19² and the rounded top construction 19¹.

The chamfered end 37 of the bolt 33 contacts with the incline 22 of the hasp 18 and is thrust rearwardly in the bolt hole 30 45 until it no longer impedes the descent of the bonnet lid 14.

When said bolt is opposite to the hole 21 in said hasp 18, it is forced through the same by the action of the coil spring 35. The 50 lock frame 24 and the hasp 18 are thereby engaged and the bonnet lid 14 and the bonnet board 15, to which they are, respectively, attached are thereby securely locked together. The construction of the lock frame 24 embodying the hasp-slot 27 ensures a rigid connection between said bonnet lock and said bonnet board and prevents excessive endwise movement of the former.

In order to release the bolt 33 from the 60 hole 21 in the hasp 18, it is necessary for a key fluted and serrated to fit the pin combination of the operating mechanism 39 to be inserted in the same and turned, where-

upon the arm 42 contacts with the pin 34 and retracts said bolt 33.

What I do claim is:—

1. Means for securing motor-cars and the like vehicles against unauthorized use and interference comprising, a lock casing attached to the inner side of the bonnet lid of said vehicle, a spring actuated latch bolt movable in said lock casing, a pin and barrel lock mechanism mounted in said casing, a rotatable member in said lock, an arm secured to said rotatable member and adapted to engage said latch bolt, and a hasp on the bonnet board of said vehicle, and having an aperture adapted to receive said latch bolt. 70

2. Means for securing motor-cars and the like vehicles against unauthorized use and interference comprising a casing attached to the inner side of the bonnet lid of said vehicle, a spring actuated latch bolt movable in said lock casing, a pin and barrel lock mechanism mounted in said casing, a rotatable member in said lock, an arm secured to said rotatable member and adapted to engage said latch bolt, a hasp on the bonnet board of said vehicle, and having an aperture adapted to receive said latch bolt, guide 90 walls in said lock casing bearing against said hasp to prevent endwise movement of said bonnet lid, and a fluted and serrated key interchangeable with either the switch lock or the bonnet lock. 95

3. In means for securing motor-cars and the like vehicles against unauthorized use and interference, an automatic snap latch on the inner side of the bonnet lid of a vehicle, a hasp secured to the bonnet board of said vehicle, and engaging said latch, and a key-actuated lock member adjacent to said snap latch and operative to release the latter from said hasp. 100

4. In means for securing motor-cars and the like vehicles against unauthorized use and interference, a lock frame mounted on the inner side of the bonnet lid of a vehicle, a hasp slot in said lock frame, a latch bolt slidably mounted in said lock frame, a bevelled end on said latch bolt, a spring actuating said latch bolt, a pin and barrel lock member secured in said lock frame, a rotatable key-actuated barrel in said lock member, an arm attached to said rotatable member and adapted to retract said latch bolt, a cover clamped between said bonnet lid and said lock frame, and a hasp secured to the bonnet board of said vehicle. 110

5. In means for securing motor-cars and the like vehicles against unauthorized use and interference, a lock frame mounted on the inner side of the bonnet lid of a vehicle, a hasp slot in said lock frame, a latch bolt slidably mounted in said lock frame, a bevelled end on said latch bolt, a spring 120

actuating said latch bolt, a pin and barrel lock member secured in said lock frame, a rotatable key-actuated barrel in said lock member, an arm attached to said rotatable member and adapted to retract said latch bolt, a cover clamped between said bonnet lid and said lock frame, and a hasp secured to the bonnet board of said vehicle, said hasp being formed with a bevelled corner, a rounded top and an inclined entrance slide 10 and having an aperture therein to receive said latch bolt.

In testimony whereof I affix my signature in presence of two witnesses.

DENIS F. DOWNES.
